UNITED STATES PATENT OFFICE.

MURIEL MARY SUTHERLAND BINNEY, OF SYDNEY, NEW SOUTH WALES, AUSTRALIA.

COT FOR CHILDREN.

No. 914,104.

Specification of Letters Patent. Patented March 2, 1909.

Application filed September 8, 1908. Serial No. 452,158.

To all whom it may concern:

Be it known that I, MURIEL MARY SUTHERLAND BINNEY, a subject of the King of Great Britain, residing at "St. Clair," Elizabeth Bay, Sydney, New South Wales, Australia, have invented certain new and useful Improvements in Cots for Children, of which the following is a specification.

My invention has for its object to provide what may be called a collapsible safety cot for children, which shall be capable of being folded up into a small compass when not in use, and which when set up shall form a rigid structure wherein a child may be left without fear of his falling out or otherwise coming to any harm.

The cot of my invention is complete in itself, that is to say the frame of the cot is devoid of parts which are necessarily detachable and thus liable to be lost; this frame comprising upright corner posts to which are permanently hinged upper and lower longitudinal and transverse rails connecting the posts together and made in sections so as to be capable of folding at the middle of the length of each in order to permit of the structure being collapsed by the uprights being brought close together. The lower rails are attached to the posts at the level of the mattress, while the upper rails, which may be attached close to the top of the posts, should be so far above the lower rails as to permit of an infant standing upright within the cot when the latter is covered in at top. Attached to the frame is a covering of open netting which may be so arranged as to become automatically distended by the setting up of the frame so as to fill the spaces at the bottom, sides, and ends of the frame, the whole of which netting may be in a single piece. The top of the cot is also designed to be covered with netting, which may be either in one with the main portion or separate therefrom and independently attachable to the frame.

In the accompanying drawings, Figures 1 and 2 are perspective views showing an example of the improved cot frame as constructed in wood, Fig. 1 showing the frame distended and Fig. 2 showing it partly collapsed. Figs. 3 and 4 are respectively side and end views showing an example of the improved cot frame as constructed in metal, the frame being distended in each case. Figs. 5 to 11 shew details of the construction illustrated in Figs. 3 and 4, drawn to a larger

scale; Figs. 5 and 6 being respectively a side elevation (partly in section) and a plan view of the upper end of a corner-post together with the associated parts, while Figs. 7 and 8 are respectively a side elevation (partly in section) and a plan view of the middle portion of a corner-post together with the associated parts. In Fig. 7 one of the horizontal rails is omitted. Fig. 9 is a separate detail view of a hinge-piece serving for the attachment of a top rail to a corner-post. Figs. 10 and 11 are respectively a side elevation and a plan view (each partly in section) of the middle joint of a top rail. Fig. 12 shows the form of the main portion of the netting.

Similar reference numerals denote corresponding parts throughout the drawings.

Referring first more particularly to Figs. 1 and 2, 1 are the four upright corner posts; 2^a, 2^b are the two sections of each of the two upper longitudinal side rails; 3^a, 3^b are the two sections of each of the two upper transverse end rails; 4^a, 4^b are the two sections of each of the two lower longitudinal side rails; 5^a, 5^b are the two sections of each of the two lower transverse end rails. The several rail-sections are hinged to the corner posts at 2^{a*}, 2^{b*}; 3^{a*}, 3^{b*}; 4^{a*}, 4^{b*}; 5^{a*} and 5^{b*} respectively. (The above references, where not shown in Figs. 1 and 2, are shown clearly in Figs. 3 and 4, hereafter described in detail). All of these hinge-joints are knee-joints permitting of flexure in one direction only, the joints of the upper rails being adapted to permit flexure downward from the posts while those of the lower rails are adapted to permit flexure upward when the cot is collapsed, as indicated in Fig. 2. The upper and lower rails are jointed to the posts toward the outside and inside of the latter respectively, as indicated, so as to be capable of passing one another when the frame is collapsed as shown in Fig. 2. When the frame is extended, the joints at 2*, 3*, 4*, and 5* may in each case be rendered rigid by means of a metal sleeve 6 embracing and adapted to slide upon the rail so as to inclose the joint, the movement of the sleeve being limited by means of a pin 7 fixed to one section of the rail and projecting through a longitudinal slot 8 of the proper length provided on the sleeve. The rigidity of the joints connecting the rails to the posts as at 2^{a*}, 2^{b*}, etc., when the frame is extended, may be insured by means of thumb screws 9 (Fig. 1) passing through holes as at 10

(Fig. 2) in the posts and entering threaded holes in the ends of the respective rails. To prevent wear, these holes are preferably lined with metal sockets wherein the screw-threads are formed. Lateral stability may be further insured by the end of each rail being formed as a tenon adapted to fit a mortise in the contiguous post, as indicated at 11 in Fig. 2.

10 Referring now to Figs. 3 to 11, it will be seen from Figs. 3 and 4, that the general arrangement is the same as that already described with reference to Figs. 1 and 2. The posts and rails, however, are formed not of wood, but of metal tubing, the material employed throughout being (for the sake of lightness) preferably an alloy of aluminium. In the example illustrated, the corner posts 1 consist each of a single length of tubing on the top of which is socketed a casting 12 for the attachment of the upper rails 2^a, 2^b and 3^a, 3^b, a sleeve 13 being slipped over and fixed on the post in position for the attachment of the lower rails 4^a, 4^b and 5^a, 5^b. The hinges connecting the upper rails to the corner-posts are formed partly by lugs 14 on the castings 12 and partly by castings 15 socketed in the ends of the rails themselves and provided with corresponding lugs 16, the hinge-pins 2^{a*}, 2^{b*}, 3^{a*}, 3^{b*}, passing horizontally through holes in both sets of lugs as shown. When the rails are extended, these hinges are locked against flexure by means of pins 17 which pass vertically through holes in tail-pieces 18 provided on the castings 15 and enter holes formed as at 19 in the tops of the castings 12, the tail pieces 18 being received in recesses in the castings 12 as indicated. The two pins 17 appertaining to the respective 40 rails which are jointed to any one corner post, are carried by a single plate 20 provided with a knob 21 forming both a handle for the plate and also a finial for the top of the post, the plate 20 normally resting upon the top of the casting 12 so that the pins 17 pass through the tail-pieces 18 and enter the holes 19 as shown in full lines in Fig. 5. When it is desired to unlock the hinges controlled by the plate 20, the latter is lifted so as to free the 50 pins 17 from the tail-pieces 18, as indicated in dotted lines in Fig. 5. In this movement the plate is guided by a rod 22 attached to it and passing through an axial hole in the top of the casting 12, the rod permitting of the 55 plate, when raised, being turned in a horizontal plane so that the points of the pins 17 may rest idly in recesses 23 (Fig. 6) provided in the top of the casting 12 and may thus retain the plate in the raised or inoperative 60 position. The lower end of the rod 22 has a head or collar 24 between which and the underside of the top-plate of the casting 12 a coiled spring 25 is confined, this spring serving normally to retain the plate 20 in operative 65 position and prevent accidental dis-

engagement of the pins 17 from the tail-pieces 18.

The hinges connecting the lower rails to the corner posts are formed partly by lugs 26 on the sleeves 13 and partly by castings 27 socketed in the ends of the rails themselves and provided with corresponding lugs 28, the hinge pins 4^{a*}, 4^{b*}, 5^{a*}, 5^{b*} passing horizontally through holes in both sets of lugs as shown in Fig. 8. When the rails are extended, these hinges are locked against flexure by means of turn-buttons 29 pivoted to the sleeves 13 as at 30 and engaging in recesses 31 in the castings 27 which may also be provided with tail-pieces 32 adapted to enter holes or recesses 32^a in the sleeves as indicated in Fig. 7.

The hinges connecting the two sections of each rail are formed in castings 33 and 34 socketed in the respective sections as shown 85 in respect of one of the upper rail joints in Figs. 10 and 11, the hinge pins 2^{a*}, 3^{a*} etc. passing through lugs 35 and 36 provided on the castings 33 and 34 respectively. Each of these hinges when the rail is extended, is 90 locked against flexure by means of a slip-bolt 37 fitted to slide, lengthwise of the rail, in a bearing provided in the casting 34, the bolt (which is concealed) being adapted to enter a socket 38 in the casting 33 and being 95 manipulated by means of a knob-handle 39 projecting laterally through a slot 40 in the wall of the tube constituting the rail. This slot has two notches 41 and 42 wherein the neck 43 of the knob-handle 39 engages when 100 the bolt 37 is at the respective ends of its travel.

The netting (Fig. 12), whereof a portion is indicated in Fig. 1, is preferably cruciform in shape so as to be capable of being applied 105 from above the upper set of rails so that the central portion 44 of the netting covers the top of the cot while the side and end flaps 45 and 46 hang downward and form walls to the space bounded by the rails and corner 110 posts. The bottom of the cot may be formed by a separate piece of netting or by extensions integral with (for example) the end flaps 46 as indicated by the dotted lines at 47, the mattress thus resting upon what 115 virtually constitutes a hammock.

The netting may be secured to the rails and corner posts in any convenient way. In the cheaper wooden construction illustrated in Figs. 1 and 2 it might for example be laced 120 directly to the frame of the cot, but (especially in the metal construction illustrated in Figs. 3 and 4) the lateral edges 48 of each flap are preferably threaded upon vertical rods 49 attached to the corresponding sleeves 125 13 on the corner posts 1, while the lower edges 48^a of the flaps are threaded upon horizontal rods 50 extending alongside of and slightly below the level of the lower rails. All of these rods are detachable from 130

the frame of the cot so as to permit of the latter being collapsed. In the case of the vertical rods 49, the lower end of each rod may be received in an eye or socket 51 fixed 5 to the corresponding sleeve 13, the upper end of the rod being secured to the casting 12 by means of a turn-button 52 which is rotatably fixed to the casting and passes through a slot in a flat palm 53 formed on the rod. The 10 opposite ends of each horizontal rod 50 may be provided with eyes or sockets 54 adapted to slide upon the corresponding vertical rods 49.

It will be obvious that the main portion of the netting might be applied from beneath 15 the lower rails instead of from above the upper rails, in which case the horizontal rods 50 would extend alongside of the upper instead of the lower rails. It will also be obvious that the horizontal rods might be 20 made in sections jointed together and to the corner posts so as to be capable of folding along with the rails; or the sections of each rod might be detachably secured to one another by means of a screw coupling or equivalent device.

The corner posts 1, if of metal tubing, may be made telescopic, the lower portion of each below the level of the sleeve 13 being adapted to slide upward into the upper or 30 main portion when the cot is collapsed, and being normally retained in the extended position by some convenient form of locking device.

What I claim and desire to secure by Letters Patent of the United States is:—

1. A collapsible safety cot for children consisting of a frame, said frame comprising upright corner posts; upper longitudinal and transverse rails hinged to said corner posts, 40 said upper rails being themselves hinged and adapted to be flexed downward, lower longitudinal and transverse rails hinged to said corner posts, said lower rails being themselves hinged and adapted to be flexed upward, said upper and lower rails being adapt-

ed when flexed to pass one another, and means for retaining said hinges in position when the parts are extended, in combination with netting distended over said rails.

2. A collapsible safety cot for children consisting of a frame, said frame comprising upright tubular corner posts, upper longitudinal and transverse tubular rails, hinges between said rails and said corner posts, said hinges being disposed toward the outside of 50 said corner posts, lugs on said hinges, said upper tubular rails being themselves hinged and adapted to be flexed downward, lower longitudinal and transverse tubular rails, 55 hinges between said rails and said corner posts, said hinges being disposed toward the inside of said corner posts, lugs on said hinges, said lower tubular rails being themselves hinged and adapted to be flexed upward, a spring pressed member mounted on each of 60 said corner posts, pins on said spring-pressed members adapted to engage holes in the lugs of the hinges of the upper rails, and holes in said corner posts, turn-buttons pivoted to 65 said corner posts and adapted to engage recesses in the lugs of the hinges of the lower rails, rods detachably secured to said frame, in combination with netting distended over 70 said rails, and secured to said detachable rods.

3. A cot of the class described, consisting of corner posts upper and lower longitudinal transverse rails hinged to the corner posts, the upper rails being offset with respect to the lower rails, and each of said rails being 75 formed of sections hinged together with a rule joint, the upper rails being adapted to fold downward, and the lower rails to fold upward, and means for locking the rails in extended position.

MURIEL MARY SUTHERLAND BINNEY.
